Primary Examiner — Patricia A Palasik(74) *Attorney, Agent, or Firm* — Knobbe, Martens, Olson & Bear, LLP(57) **CLAIM**

The ornamental design for a bioprinter assembly, as shown and described.

DESCRIPTION

FIG. 1 is front elevational view of a bioprinter assembly, showing our new design;

FIG. 2 is a left side elevational view thereof;

FIG. 3 is rear elevational view thereof;

FIG. 4 is a right side elevational view thereof;

FIG. 5 is a top plan view thereof;

FIG. 6 is a bottom plan view thereof;

FIG. 7 is a front, left, top perspective view thereof;

FIG. 8 is front elevational view of a bioprinter assembly, in an alternate condition of use, without the transparent shield at the top;

FIG. 9 is a left side elevational view thereof;

FIG. 10 is rear elevational view thereof;

FIG. 11 is a right side elevational view thereof;

FIG. 12 is a top plan view thereof;

FIG. 13 is a bottom plan view thereof;

FIG. 14 is a front, left, top perspective view thereof; and, FIG. 15 is an enlarged front view of a bioprinter head on the front of the bioprinter assembly shown removed for clarity.
